UNITED STATES PATENT OFFICE.

FRANZ A. BOEDTCHER, OF BERGENFIELD, NEW JERSEY.

ELECTRIC SWITCH.

Application filed May 19, 1923. Serial No. 639,999.

This invention is an electric switch and while adapted for general use is particularly intended for employment in conjunction with the resetting circuits of elevator signaling systems. In systems of this character, it is desirable to close certain of the resetting circuits momentarily, but, in practice, and prior to the present time, considerable difficulty has been experienced in obtaining apparatus which would close such circuits for just the desirable period. The switch of the present invention enables a substantially momentary contact to be obtained and at the same time insures that this momentary contact will be of sufficient duration to enable the circuit or circuits which it controls to properly carry out its functions.

With these considerations in mind, the switch of the present invention embodies mechanism electrically operable by a motor circuit, controller circuit or by some other circuit associated with either of these circuits for the purpose of bringing normally spaced contacts of a signal resetting circuit into engagement and subsequently out of engagement with respect to one another and for controlling the time factor of such engagement, so that while the contact may be said to be a momentary one, its duration is such that the electrical adjuncts in said resetting circuit will operate to carry out their functions during the actual period of engagement between said contacts.

The present invention thus obviates certain difficulties in prior practice arising from the operation of the resetting circuit through too short a period to effect resetting of the signals and also arising from the energizing of the resetting circuit for a period greater in excess to that required for its functioning, the result of the latter course usually being the burning out of magnets included in such circuit.

In my prior Patent No. 1,333,240, issued March 9th, 1920, I disclosed a pump operated switch intended for the purpose of timing the period of operation of an electrical circuit, but in that instance the pump was mechanically operated directly from some movable part of the elevator installation, preferably the overhead. Practice has proven that when used in this connection, it is subjected to excessive wear and moreover it was found that the pump could not be absolutely relied upon in the event that the car was run very slowly between the several floors. In other words,

the action of the pump to control the switch was too sluggish in its operation and there was no uniformity in the contact period. With the present invention, in contradistinction, the contact period will be uniform irrespective of the speed of the car and will be constant under all conditions.

A further feature of the present invention resides in the fact that the switch of this invention may be regulated to give the desired time interval between circuit closing and opening, thereby enabling perfect adjustment of the parts to the particular installation with which it is associated.

While the invention may partake of different practical forms, it consists in one of its practical embodiments in a solenoid coil included in a suitable circuit and with this coil is associated a core operative within a cylinder coaxially of the coil of the solenoid. The cylinder is adapted to contain fluid. The core normally gravitates to the lower end of the cylinder and by such operation causes the float to be forced into the upper portion of the cylinder. However, when the solenoid coil is energized, the core is drawn upwardly, creating a partial vacuum beneath it which causes the fluid to pass by the core into the lower portion of the cylinder during which operation the movement of the core is relatively sluggish depending upon the adjustment of the parts. When the coil is deenergized the core again descends by gravity under the cushioning effect of the fluid which returns to the upper part of the cylinder past the core.

By controlling the normal position of the core with reference to the coil of the solenoid, the speed of operation of the core may be varied or regulated. The core is utilized to actuate a switch which is adapted to be closed and subsequently opened by the movement of the core, so that by regulating the speed of movement of the core or its travel, the closing and opening of the switch may be properly timed.

Features of the invention, other than those specified, will be apparent from the herein-after detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is an elevation of switch and operating mechanism embodying the present invention.

Figure 2 shows the construction of Figure 5 1 with the operating apparatus in central section; and,

Figure 3 is a section of a valve associated with the core and this section is taken on the line 3-3 of Figure 2.

10 Referring to the drawings, 1 designates an elongated tube or cylinder closed at its lower end as by a rubber plug 2 and guided for vertical adjustment in brackets 3 formed on a switch plate 4. The bracket 3 has a depending flange 5 which is tapped to receive two screws 6 which pass through slots 7 in a supporting plate 8, the lower end of which is bent forwardly at right angles to the plate 8 and forms a foot adapted to support the lower end of the cylinder 1. The cylinder may be vertically adjusted by loosening the screws 6 and sliding the supporting plate 8 vertically and thereupon again tightening the screws 6 to lock it in position.

25 Encircling the cylinder 1 between the brackets 3 is a solenoid coil 9. In practice, this coil may be in the form of a winding, but for the purpose of illustration I have shown two coils connected in series by a wire 30 10. These two coils however function as a single coil. The coils 9 are maintained in position by pressure screws 11 which are threaded through the upper bracket 3 and bear on the top of the coils to clamp them 35 tightly against the lower bracket 3. The coils are thus mounted in fixed position while the cylinder is longitudinally adjustable coaxially of the coils.

40 The core 12 of the solenoid is cylindrical and is loosely positioned within the cylinder 1 as shown best in Figure 2. With this top 45 is associated a disc valve or piston 13 adapted to fit the interior of the cylinder more tightly than the core 12. The stem 14 of the core extends upwardly through a hole in the center of the valve 13, the hole 15 of which valve is somewhat larger than the stem 14 as shown in Figure 3, so as to permit 50 fluid to pass through the hole 15 and around the stem 14. The bottom of the valve is shown as substantially flat but with radial channels 16 through which fluid is adapted to circulate.

55 The solenoid is included within a suitable circuit 17, which when energized, energizes the coil and causes the core to be elevated. The cylinder 1 contains a fluid which when the core is depressed is displaced by the core and forced into the upper part of the cylinder. However, when the core is raised under the impulse of the coils, a partial vacuum is produced within the lower part of the cylinder and below the valve 13 and the core can only be elevated by the coil at a speed substantially proportional to the rate at

which the fluid can flow from above the valve past the valve and into the lower portion of the cylinder. Thus the speed of the core in an upward direction under the impulse of the coils is controlled by the speed with which fluid can pass by the valve and into the lower part of the cylinder. The speed of the core will therefore be held down so that its movement will be relatively slow or at least much slower than would be the case if it were not under the cushioning action of the partial vacuum created through this movement. 70 75

When the coil is deenergized, the weight of the core will cause it to return to the bottom of the cylinder and in so doing its weight will be imposed upon the fluid which will be forced upwardly past the valve to its initial position in the upper portion of the cylinder. The operation of the core in both directions will therefore be cushioned and its movement will be relatively sluggish.

The relatively slow movements of the core as described are utilized to operate one or more electric switches and while the switch construction may vary, I have shown the switch as consisting of a bell crank pivoted at its elbow on a bolt 18 passing through plate 4. One arm 19 of the bell crank is connected to the stem of the core 12 by means of a link 20, while the other arm 21 of said bell crank constitutes a switch arm. The bell crank is insulated from the plate 4, which, in practice, may be of fibre although it may be of metal with suitable insulating plates and bushings. As the core is vertically reciprocated, it will, manifestly, oscillate the bell crank on its fulcrum 18 and in so doing will cause the arm 21 to be swung back and forth for the purpose of bringing contacts associated therewith into and out of engagement with fixed contacts carried by the plate 4. Any number of contacts may be associated with the arm 21 and they may be secured thereto in different ways. However, for the purpose of illustration, I will describe the structure as shown in the drawings.

In this showing, current is led through wire lead 22 to a metallic plate 23 which is in electrical contact with the bolt 18 and in order to assure absolute electrical connection between the bolt and the bell crank I may secure said bolt to the bell crank by a flexible lead 24, as shown in Figure 1, so that perfect electric connection will result. Current is therefore fed through the lead 22 to the bell crank which forms one terminal of the circuit.

25 designates a metallic plate to which is secured a wire lead 26 and to this metallic plate is pivoted a contact 27, the right hand side of which is exposed to contact with the lower end of the arm 21, while the opposite side of which has secured thereto an insulat- 125 130

ing strip 28. A spring 29 normally maintains the contact 27 in upstanding position and in the path of a knob 30 formed at the lower end of the arm 21 of the bell crank. 5 With this construction, it will be apparent that when the solenoid is energized, the core will be elevated and will oscillate the bell crank in a clockwise direction as viewed in the drawings to bring the knob 30 into engagement with the uninsulated part of the contact 27 for the purpose of completing the circuit between the leads 22 and 26. The knob 30 will engage with the contact 27 while the latter is in upstanding position 10 and as the bell crank is slowly tilted it will force the contact 27 from the dotted line position of Figure 2 into the full line position of this figure against the tension of the spring 29 and this operation will continue until the contact 27 has been tilted far enough for the knob 30 to ride past the end of said contact whereupon the spring 29 will immediately return the contact to upstanding position, thus breaking the circuit which 20 was previously made. The circuit will remain open no matter how long the solenoid remains energized and when it is deenergized and the core proceeds to descend, the swinging of the arm 21 back into its normal position will cause the knob 30 to engage with the insulating strip 28 and rock the contact 27 far enough to permit the knob to pass by this contact without however having completed this circuit during such return 30 movement. It will thus appear that by regulating the speed with which the core is elevated under the impulse of the coils, the duration of contact between the knob 30 and the contact 27 and the consequent duration 35 of energizing of the circuit of which the leads 22 and 26 form a part may be controlled. The speed with which the core will be elevated will depend upon the adjustment of the supporting plate 8 since the lower 40 45 the core is permitted to normally gravitate the slower will be its elevation not only because it will have a longer distance to travel, but because it will be further removed from the magnetic center of the coils. I am thus able by regulating the position of the cylinder to regulate the interval or duration of the energizing of the circuit 22-26.

Additional switch mechanism may if desired be associated with the arm 21, such for 50 example as the arm 31, which is pivoted to the arm 21 at 32 and is adapted to engage with the fixed contact 33 having an associated lead 34. The arm 31 is shown as provided with an insulating strip 35 which when 55 the arm 21 is in normal position engages with the contact 33 and breaks the circuit of which the lead 34 forms a part. However, when the arm 31 is oscillated by the core, the uninsulated part of the arm 31 will make 60 65 electrical connection with the contact 33

and will maintain this electrical connection until the parts are restored to normal. A number of switches similar to the switch 31 may be associated with the arm 21 and the insulating strips 35 may be so associated as to either permit normal electrical connection or electrical connection only when the arm 21 is operated.

In the foregoing detailed description of the invention, I have referred to a fluid as contained within the cylinder 1 and I wish this phraseology to be construed broadly as meaning any fluid. This I may use either air, liquid or a gas, though in practice I preferably use one of the light oils such for example as kerosene, the evaporation of which is very slow and which liquid is sufficiently light and mobile, so as not to render the operation of the solenoid unduly sluggish. In practice, the cylinder 1 may be of glass, but I preferably make it of brass or copper and in such cases associate with the cylinder a sight tube or gauge glass 36 which not only serves to show the height of the liquid, but also serves as a reservoir to compensate for slight evaporation.

It will be noted that in the foregoing detailed description of the invention I have not attempted to state the particular circuits of which the leads 22, 26 and 34 form parts as this is really immaterial. However, these leads are usually parts of the resetting circuits of an elevator signalling system wherein it is desirable to obtain a substantially momentary energization thereof, but one of sufficient duration to insure proper operation of the electrical instruments included in such circuits. I wish it understood however that I do not limit the invention to the particular circuits shown or to the particular arrangement of circuits or to the specific switch construction illustrated, as variations in this switch structure will readily suggest themselves to those skilled in the art.

The coils of the solenoid may be introduced or associated with the motor circuit, the controller circuit or with any other circuit, either in series or multiple or, said coils may be included in independent circuits adapted to be controlled by any movable part of the elevator installation.

The invention is therefore to be understood as not limited to the specific showing of the drawings but is to be understood as fully commensurate with the appended claims.

Having thus fully described the invention, what I claim as new and desire to secure by Letters Patent is:

1. In an apparatus of the character described, the combination with a switch of an upstanding cylinder closed at its lower end and containing a liquid, a solenoid coil embracing a portion of the length of said

- cylinder, a solenoid core within the cylinder and normally positioned in removed relation to the magnetic center of the coil, valvular means associated with said core to permit liquid in the cylinder to by-pass the core during movement of the latter longitudinally of the cylinder to cushion the operations of the piston, and mechanical connections between the core and the switch for securing these parts to one another.
2. In an apparatus of the character described, switch mechanism embodying a pivoted lever, circuit closing means connected with the work arm of said lever, in combination with an upstanding cylinder closed at its lower end and containing a liquid, a solenoid coil embracing a portion of the length of said cylinder, a solenoid core within the cylinder and normally positioned in removed relation to the magnetic center of the coil, valvular means associated with said core to permit liquid in the cylinder to bypass the core during movement of the latter longitudinally of the cylinder to cushion the operations of the piston, and mechanical

connections between the core and the power arm of said lever for securing these parts together.

3. In an apparatus of the character described, switch mechanism embodying a pivoted lever, circuit closing means connected with the work arm of said lever, in combination with an upstanding cylinder closed at its lower end and containing a liquid, a solenoid coil embracing a portion of the length of said cylinder, a solenoid core within the cylinder and normally positioned in removed relation to the magnetic center of the coil, valvular means associated with said core to permit liquid in the cylinder to bypass the core during movement of the latter longitudinally of the cylinder to cushion the operations of the piston, mechanical connections between the core and the power arm of said lever for securing these parts together, and means for regulating the position of the cylinder with respect to the coil.

In testimony whereof I have signed the foregoing specification.

FRANZ A. BOEDTCHER.
